UNITED STATES PATENT OFFICE

2,081,324

MACHINE FOR WAXING PAPER

Lloyd L. Dodge, Rhinelander, Wis., assignor to
Rhineland Paper Company, Rhinelander,
Wis., a corporation of Wisconsin

Original application October 12, 1932, Serial No.
637,421. Divided and this application March 9,
1935, Serial No. 10,227

6 Claims. (Cl. 91—46)

This invention relates to a machine for waxing paper. More particularly the invention relates to an apparatus for preparing waxed paper of increased transparency.

5 This application is a division of my co-pending application, Serial No. 637,421, filed October 12, 1932.

10 So-called "waxed paper" has been generally prepared by passing paper through a bath of molten "wax", chilling the wax coated paper to harden the wax, and winding the waxed paper into rolls. Ordinarily, the paper is submitted to but a single immersion in the bath of molten wax, but it has also been suggested to pass the 15 paper through successive baths, or to prolong the time of immersion of the paper in a single bath in order to increase the amount of penetration of the wax into the paper.

15 My present invention contemplates a machine for waxing paper, whereby the transparency of the waxed paper is still further enhanced. In my machine or apparatus, the paper is subjected to a pre-waxing step, wherein the wax is caused to penetrate into and thoroughly impregnate the fibers of the paper. This step is followed by a second waxing step carried out in the usual manner.

20 It is therefore an important object of this invention to provide a machine for preparing wax paper of increased transparency.

25 It is a further important object of this invention to provide a converter apparatus that is simply and efficiently operated to form waxed sheets of increased transparency and flexibility.

30 Other objects of this invention will become apparent from the following description and appended claims.

35 This invention (in a preferred form) is illustrated on the drawings and hereinafter more fully described.

On the drawings:

Figure 1 is a side elevational view of apparatus embodying the principles of my invention.

Figure 2 is a top plan view of the apparatus 45 shown in Figure 1.

Figure 3 is an enlarged sectional view taken substantially along the line III—III of Figure 2, with parts in elevation.

Figure 4 is an enlarged broken sectional view taken substantially along the line IV—IV of Figure 3.

Figure 5 is an enlarged broken fragmentary sectional view taken substantially along the line V—V of Figure 4.

As shown on the drawings:

Reference numeral 1 indicates generally a housing supported on a flooring 2, for enclosing elements of a machine for pre-waxing paper. Said housing 1 comprises an L-shaped compartment 3 having top and side walls and an open bottom and a closed compartment 4. Both compartments 3 and 4 are provided with hinged covers such as the covers 5, 6 and 7 respectively. An unwinding stand 8 for supporting a roll of paper 9 is mounted in the open space 10 defined by the L-shaped compartment 3, so as to be readily accessible at its ends through the opening 10. It should be understood that the unwinding stand 8 is of any conventional construction, and may be provided with suitable means for tensioning the paper web as it is unwound from the roll 9.

15 A chilled roll or sweat roll 11 is supported on pedestals 12 in the compartment 3 adjacent the short leg thereof. The roll 11 comprises a hollow shell communicating through a hollow trunnion, as at 13, with a source of cold water or brine that is circulated through the shell and out through the other hollow trunnion 14. The hollow trunnions 13 and 14 are suitably journaled in bearing brackets 15 and 16 respectively supported from the side walls of the compartment 3.

20 A steam spray pipe 17 is mounted parallel to and closely adjacent to the periphery of the sweat roll 11 and is provided with a plurality of perforations 18 (Fig. 4) through which steam may be directed toward the surface of the roll 11.

25 The compartment 4 constitutes a tank having a false bottom 19 (Fig. 3) and four side walls 20, 21, 22 and 23. Beneath the false bottom 19

30 is a space for heating elements such as steam coils 24 (Fig. 3). The heating coils serve to keep molten the wax in the bath 25 maintained above the false bottom 19 at a suitable level. A winder shaft 26 is mounted above the bath 25

35 with its ends suitably journaled in bearings 27 and 28 (Fig. 4). Said bearings 27 and 28 are supported on side extensions 29 and 30, respectively, formed on the side walls 20 and 22 of the compartment 4.

40 Adjustable end flanges 31 and 32 are held in position by means of collars 33 and 34, respectively, at the ends of the roll portion of said winder shaft 26 to insure an even winding of the web of paper on the roll portion 26.

45 As the web is unwound from the roll 9, it passes around the sweat roll 11 and then over a small idler roller 35, mounted in the compartment 4 adjacent to and slightly above the upper edge of the wall 23. In adjustable roller 36

(Figs. 3, 4 and 5) is mounted at its ends in bearings 37 secured to vertically movable racks 38 extending along the side walls 20 and 22 of said compartment 4. Said racks 38 are movable 5 within guideways 39 affixed to the side walls 20 and 22 and are adapted to be moved up or down by means of pinion gears 40, mounted on a transverse shaft 41. One end of said shaft 41 extends through the wall 20 (Fig. 4) and is provided with 10 a wheel or handle 42 for manual operation.

In threading the paper through the apparatus, above described, the web of paper 43 is drawn from said roll 9 around the sweat roll 11 and over the idler roller 35. The roller 36 is adjusted to lie above the surface of the bath 25 to permit the end of the web 43 to be passed under it and then the roller 36 is lowered into the bath so as to lie completely beneath its surface. The end of the web 43 is then started 20 around the winder roll 26. Any suitable source of power such as the motor 44, belt 45 and pulley 46, may be used to drive the winder shaft 26a on which the roll 26 is mounted (Fig. 2). The rotation of the roll 26 in a counter-clockwise direction draws the web 43 through the bath of molten wax. In operation, the wax in the bath 25 is kept at a temperature sufficiently above its melting point to insure thorough penetration of the wax into the fiber of the web. 25

No means are provided for removing the excess wax from the web as it passes out of the bath other than the effect of gravity in causing any large excess carried up with the web out of the bath to flow back into the bath. The wax coated 30 web is wound up into a roll on the winder shaft 26 while the wax is still in a molten condition, and because of the fact that the compartment 4 is entirely enclosed, the roll of coated paper on the winder shaft 26 is maintained so long as it 35 remains in said compartment 4 at a temperature above the softening point, and preferably substantially above the melting point of the wax. The purpose of this is to permit the wax to penetrate and thoroughly impregnate the individual fibers of the web 43. To fully accomplish 40 this purpose, the roll of coated paper on the winder shaft 26 is allowed to remain within the heating compartment 4 until substantially complete penetration and impregnation of the wax 45 into the paper has taken place. 50

After the wound, coated web of paper has remained for a sufficient length of time within the compartment 4, it is removed and immediately subjected to the usual waxing step on any suitable conventional type of waxing apparatus such as is indicated at A in Figures 1 and 2. As there illustrated, the roll 50 of the pre-waxed paper is mounted on an unwinding stand and the coated web 52 is led through a bath of molten wax held 55 in a container 53 where it receives an additional coating of wax. From the container 53 the waxed web is passed between squeeze rolls 54 and 55 and around a plurality of cooled drums 56 to a winder shaft 57. Inasmuch as the apparatus A may be of standard or conventional construction, it is deemed unnecessary to give any further description of it. It will be understood, of course, that instead of passing the paper 60 through a bath of molten wax, the wax may be sprayed or otherwise applied to the traveling web 52.

The converter apparatus of this invention provides for a pre-waxing step which gives enhanced 65 transparency to the final waxed sheet because it

insures a thorough penetration of the wax into the paper and a full impregnation of the fibers of the paper to give a continuity of the wax substantially free from fissures and cleavages therein. The absence of such fissures and cleavages is believed to be responsible for the increased transparency of the sheet, since the presence of planes of cleavage in the crystalline wax structure would naturally bring about a refraction and diffraction of light passing through the waxed 10 sheet.

The purpose of the sweat roll 11 and the steam pipe 17 is to increase the moisture content of the web of paper prior to the pre-waxing step, so as to increase the flexibility of the waxed 15 sheet. As paper ordinarily comes from a paper machine, in the manufacture of sulphite or glassine paper, it contains between 4% and 8% moisture. Quite generally the moisture content is nearer the lower limit. Subsequently, as the 20 paper web passes into contact with the chilled surface of the roll 11 on which moisture from the steam projected through the pipe 17 has condensed, the web of paper picks up additional moisture to bring the moisture content up to 25 between 8% and 15%. Since the paraffine waxes which are generally employed for the waxing of paper have melting points considerably below the boiling point of water (being generally in the neighborhood of between 50 and 60° C.) a considerable amount of moisture that is thus introduced into the sheet is retained in the paper during and after the waxing operation. The coating of the wax applied to the paper serves to aid the fibers in retaining the moisture and thus keep the fibers pliable and flexible. Cellulose fibers are hydroscopic in character and normally absorb, when exposed to a moist atmosphere, a fairly definite quantity of moisture, in the neighborhood of 10% by weight. On the other hand, 30 if the fibers are dried out excessively on the machine and no moisture is subsequently added, they are relatively brittle, and after being coated with the wax are unable, under ordinary circumstances, to re-acquire a sufficient moisture 35 content to render them flexible and pliable. The step of moistening the paper as provided by my converter apparatus prior to the pre-waxing step is, therefore, an important feature of my invention. 40

I am aware that many changes may be made and numerous details of construction may be varied through a wide range without departing from the principles of this invention, and I, therefore, do not purpose limiting the patent 55 granted hereon otherwise than necessitated by the prior art.

I claim as follows:

1. A converter apparatus for conditioning and waxing paper, comprising, in combination, a 60 closed compartment having a cover permitting access to the interior thereof, means at the bottom of said compartment adapted to receive a bath of molten wax, means for maintaining said wax in molten condition and for heating said compartment, a roll wholly within said compartment in spaced relation from the bottom thereof, means for driving said roll, guide tracks mounted on the side walls of said compartment adjacent one end thereof, racks slidable in said tracks, a guide roll 65 rotatably mounted on said racks, means to raise and lower said racks to thereby vertically adjust said guide roll in the compartment, a hood adjacent said compartment, means for creating a moist atmosphere within the hood, and means for 70

directing the web of paper passing through the hood into said compartment.

2. A converter apparatus for conditioning and waxing paper comprising, in combination, a closed compartment having a cover permitting access to the interior thereof, a false bottom therein, heating means below said false bottom, a roll wholly within said compartment in spaced relation from the bottom thereof, means for driving said roll, 5 guide tracks mounted on the side walls of said compartment adjacent one end thereof, racks slideable in said tracks, a guide roll rotatably mounted on said racks, pinion gears enmeshed with said racks to raise and lower the same thereby adjusting the guide roll vertically in the compartment, a hood adjacent said compartment, means for guiding a web of paper through said hood, means for moistening said web of paper as it enters the hood and means for guiding the paper 10 passing through the hood into said compartment.

3. A converter apparatus for conditioning and waxing paper comprising a hood having top and side walls, a chill roll mounted in one end of said hood, means for moistening the periphery of said chill roll, a closed compartment at the other end of said hood, said compartment being adapted to receive a wax bath in the bottom thereof, means for heating said compartment and maintaining the wax bath in a molten condition, a winder roll 15 in said compartment above the wax bath, means for driving said roll, and means for feeding a web of paper through said hood to be moistened therein, and into said compartment to be thoroughly impregnated with wax.

35 4. A converter apparatus for conditioning and waxing paper comprising an elongated tunnel-like hood, means for supplying a moist atmosphere within said hood, means for directing a web of paper through said hood, a closed compartment at 10 the other end of said hood, said compartment having a wax bath therein, means for directing the

web of paper from said hood into said wax bath, a driven roll above said wax for receiving the web of paper from the bath and means for heating said compartment.

5. A converter apparatus for conditioning and waxing paper comprising a closed compartment for receiving a wax bath therein, means for heating said compartment and maintaining the wax bath in a molten condition, a winder roll in said compartment above the wax bath, means for driving said roll, a vertically adjustable guide roll in said compartment adjacent one end thereof adapted to be lowered into the wax bath, an L-shaped hood adjacent said compartment having top and side walls, a chill roll in said hood adjacent the short leg thereof, means for moistening the periphery of said roll and a reel stand mounted below the hood for supplying a web of paper for travel over the chill roll through the hood to the heated compartment. 15

6. A converter apparatus for conditioning and waxing paper comprising a closed compartment for receiving a wax bath therein, means for heating said compartment and maintaining the wax bath in a molten condition, a winder roll in said compartment above the wax bath, means for driving said roll, a vertically adjustable guide roll in said compartment adjacent one end thereof, said roll adapted to be lowered into the wax bath, an L-shaped hood adjacent said compartment having top and side walls, a hollow roll mounted in said hood adjacent the short leg thereof, means for circulating a cooling medium through said roll, a perforated roll extending axially in spaced relation in front of said hollow roll, means for supplying steam through said perforated roll to moisten the periphery of said hollow roll and means for feeding a web of paper over said hollow roll and through said tunnel to the heated compartment. 20 25 30 35 40

LLOYD L. DODGE.
